Firm LLC**(57) CLAIM**The ornamental design for a flexible electronic device, as
shown and described.**DESCRIPTION**FIG. 1 is a perspective view of a flexible electronic device
showing the new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the new design shown in a
first bending position;FIG. 9 is a left side view of the new design shown in a
second bending position;

FIG. 10 is a top view of FIG. 9;

FIG. 11 is a bottom view of FIG. 9;

FIG. 12 is a perspective view of FIG. 9;

FIG. 13 is a perspective view of the new design shown in a
third bending position;FIG. 14 is a left side view of the new design shown in a
fourth bending position;

FIG. 15 is a top view of FIG. 14;

FIG. 16 is a bottom view of FIG. 14; and,

FIG. 17 is a perspective view of FIG. 14.
